UNITED STATES PATENT OFFICE.

WILLIAM WHITWORTH, OF CLEVELAND, OHIO.

DESIGN FOR A SEWING-MACHINE CASE.

SPECIFICATION forming part of Design No. 12,700, dated January 17, 1862.

Application filed August 2, 1880. Term of patent 3½ years.

To all whom it may concern:

Be it known that I, WILLIAM WHITWORTH, a citizen of the United States, residing at Cleveland, in the county of Cuyahoga and State of Ohio, have invented and produced a new and original Design for Sewing-Machine Cases, of which the following is a specification, reference being had to the accompanying drawing, forming part thereof.

10 The figure is a perspective view of my newly-designed sewing-machine case.

Heretofore sewing-machine cases have been made with square top and corners, with paneled sides and ends.

15 The leading feature in my design consists in slanting the upper corners on the front and rear sides, thus narrowing the front and rear sides, and also the top, giving the case a much neater appearance.

20 A represents the front side of the case, finished with a round end central panel, a, flanked by four raised corner-panels, b b. These panels may be finished with molded edges and veneered with fancy veneering, as desired. The base of the case is finished with

a deep molding, c. The slanting portion of the sides is covered with a wide molding, D, in ogee pattern, with the lower edge projecting over the sides and the ends projecting over the ends of the case. The under side of said 30 molding D is flat, and is secured to the slanted ends of the case and to the upper edge of the sides. The top E covers the space between the upper edges of the two slanting moldings D, and has a beveled or molded edge. The 35 two front perpendicular corners of the case are chamfered off and ornamented with a turned piece or post, F.

I claim—

A design for sewing machine cases, consisting in the combination, with a case having inclined upper side edges, of the molding D, the elongated ovals and corner-pieces b, and the ornamental posts F, the latter secured to the corners of the case, substantially as set forth. 40 45

WM. WHITWORTH.
